Primary Examiner — Thomas Johannes*Assistant Examiner* — Catherine Ho(74) Attorney, Agent, or Firm — Seyfarth Shaw LLP(57) CLAIM

The ornamental design for a decorative gusset, as shown and described.

DESCRIPTION

FIG. 1 is a top perspective view of a decorative gusset;

FIG. 2 is a top view thereof;

FIG. 3 is a rear view thereof;

FIG. 4 is a front view thereof;

FIG. 5 is a left-side view thereof; and,

FIG. 6 is a right-side thereof.

The broken lines depict environmental subject matter only and form no part of the claimed design.

The dot-chain lines illustrate a border of the claimed subject matter and form no part of the claimed design.

1 Claim, 3 Drawing Sheets(56)
